UNITED STATES PATENT OFFICE.

LEOPOLD WEISCOPE, OF NEW YORK, N. Y.

BOTTLE-RINSING MACHINE.

971,231.

Specification of Letters Patent. Patented Sept. 27, 1910.

Application filed October 25, 1909. Serial No. 524,356.

To all whom it may concern:

Be it known that I, LEOPOLD WEISCOPE, a citizen of the United States, and resident of New York, in the county of New York and State of New York, have invented certain new and useful Improvements in Bottle-Rinsing Machines; and I do hereby declare that the following is a full, clear, and exact description thereof.

10 The object of my invention is to provide a rapid, simple and economical bottle-rinsing machine, its construction and arrangement being such that the machine is capable of adjustment, whereby bottles of various 15 sizes may be cleaned, the bottles being placed over nozzles carried by a slowly revolving sectional reel, through which reel, water is successively admitted to the sections thereof at a predetermined point in its rotation, 20 whereby the bottles of each reel-section are cleaned both interiorly and exteriorly. Thus the bottles are handled by a single operation, being inserted upon the nozzles and removed therefrom after having completed 25 a revolution of the reel in a thoroughly cleaned condition, while the utilized water is caught in a stationary metallic basin and discharged therefrom through a waste-pipe.

The invention therefore consists in what 30 is herein described with reference to the accompanying drawings and subsequently claimed.

In the drawings: Figure 1 represents a 35 vertical sectional view of a rinsing-machine embodying the features of my invention, with portions of the mechanism broken away; Fig. 2, a plan view of the same, with parts broken away and parts in section to better 40 illustrate the details; Fig. 3, a detail sectional elevation of the machine looking toward the rinsing-side thereof, the section being indicated by line 3-3 of Fig. 1, and Fig. 4, a detail plan view of fixed water-distributing rings utilized in connection 45 with the reel-hub.

Referring by numerals to the drawings, 1 indicates a hollow standard in which is secured a gear-box 2, that also serves as the 50 lower bearing for a vertical spindle 3, the upper bearing of the spindle being had in a sleeve 4 that extends from the standard. Motion is imparted to the spindle through a pulley 5 fast in a shaft carried by the gear-box, between which shaft and spindle 55 within the box is interposed a suitable system of reduction-gearing the latter forming

no part of the invention and therefore is not shown.

A flanged cup-portion 6 of the standard has secured thereto the inclined bottom of a 60 basin 7, the latter being provided with an annular wall 8, that forms a casing for the rinsing apparatus. Keyed to the upper end of the spindle is a hub 9 provided with a series of hollow spokes 10, the lower face 65 of the hub being countersunk for the reception of a channeled ring 11, which ring surrounds the spindle and is faced to effect a water-tight joint in connection with the countersunk face of the hub. The channeled ring 11 carries two or more depending rods 12, one of which only is shown. The ends of these rods engage apertures in a flange 4^a that extends from the sleeve 4 of the standard. The rods are threaded adjacent to the ring for the reception of adjusting nuts, between which nuts and the sleeve flange 4^a are interposed coil-springs 13 adapted to hold said ring securely to its seat. In order to hold the ring against rotation, the latter is provided with a depending slotted ear 14, the slot in which ear straddles lug 15 that extends from the standard sleeve.

Connecting with the channel of ring 11 85 and the upper face thereof, is a segmental aperture 16, which aperture is arranged to register with circular openings 17 that lead from the hollow spokes 10 to the outer face 90 of the hub-portion thereof. Each hollow spoke 10 communicates with a radially channeled web 18 of a sector, the web of each sector being bolted to its respective spoke. Each of the sectors comprises a pair 95 of coinciding annular tubular or hollow members 19, which members are connected by the radial channels 18, the ends of the hollow members 19 being closed by radial plugs 20 that abut each other and are secured together to form a pair of interruptions 100 for the water channels. These channels in turn are fed by the spokes 10, from the channeled ring 11, as each opening 17 of the respective spokes passes over the segmental aperture 16 of said channeled ring.

105 Water-supply is admitted to the ring 11 by means of a valve-controlled supply-pipe 21, which pipe passes through the bottom of basin 7 and is tapped into the ring-channel, as shown.

110 From the foregoing it will be seen that the annular hollow members 19 together

with the hubbed spokes and spindle constitute a rotatory reel, the sections of which reel are fed by water at intervals while they are passing the segmental feed aperture 16 in the non-rotatory ring.

The tubular members 19 of the sectors are tapped for the reception of a series of vertically disposed spray-nozzles 22 that are provided with suitable end perforations, 10 through which perforations water is discharged within bottles placed over the spindle. In order that bottles of various sizes may be cleaned over nozzles of a maximum length effectually, provision is made for 15 regulating the distance between the bottom of the bottle and spray-end of the nozzle. The means employed comprise an adjustable bottle-rest in the form of a sheet-metal ring 23, the ring being provided with apertures 24 through which the nozzle 22 project. The apertures 24 are slightly longer in diameter than the diameter of the nozzles, said apertures being pressed or otherwise formed with downwardly curved edges, whereby the 20 spent water is freely conducted from the interior of the bottles and through the aforesaid aperture. The spent water is finally caught by the basin and discharged through a waste-pipe 25 that is connected to the 25 standard cup. The sheet-metal ring is supported by posts 26 secured to the webs 18 of the sectors, which posts pass through apertures in the ring and collars 27 that are secured to the upper face of said ring, the 30 collars being provided with set-screws for engagement with the posts, whereby the aforesaid ring 23 may be held at various elevations with respect to the nozzle ends. Thus if a lot of small bottles are to be 35 cleaned, the ring would be set at a correspondingly high elevation, as shown in Fig. 1 of the drawings, but should large sized bottles, such as indicated at X, be cleaned, it is obvious that the sheet-metal ring or 40 bottle-rest would be dropped downward, whereby the nozzles would extend farther into the bottles in order that the same may be more firmly supported and their bottoms more effectually reached by the water-spray. 45

50 That portion of the basin wall 8 opposite the segmental aperture 16 of the channeled ring, is provided with a hood 28, which hood is secured to the wall and has a roof-portion that extends over the hollow members 19 of the reel, the hood serving as a deflector to throw the waste water that escapes or spatters from the nozzles at this point into the basin. The roof of the hood also serves as a support for the bottle-shield 29 that 55 is hung from said roof by posts 30, which posts project from the shield and are adjustably secured in bosses 31 of the hood roof, being held in adjustment by set-screws in threaded engagement with the bosses, as 60 best shown in Fig. 3. This shield is ad-

justed to the height of the bottles being rinsed, whereby the bottoms of the bottles will engage the shield if lifted by the force of the water and thus prevent the same from being displaced from the nozzles. The 70 shield is especially necessary in the operation of the machine when small or light weight bottles are being cleaned, it being understood that the length of said shield is only of such proportions as to hold those 75 bottles which are being rinsed upon a single section of the reel.

To clean the exterior of the bottles a valve-controlled branch-pipe 32 extends from the main supply-pipe over the hood 80 roof, the end of the branch-pipe being in hose-connection with a perforated pipe-section 33, which section is secured to the upper face of the bottle-shield 29, the shield in this instance being provided with perforations 85 through which water from the perforations of the pipe-section 33 passes and is distributed upon the outside of the bottles as they travel thereunder, this water being also caught by the basin 7 and discharged into 90 the waste-pipe.

From the foregoing description it is apparent that in using the machine, the operator standing at one point places the inverted bottles to be rinsed upon the nozzles 95 as the reel slowly revolves, when the spoke opening 17 of the sector upon which the bottles have been placed, reaches the segmental aperture 16 of the ring, the bottles thereon have passed under the bottle shields 100 29. Water is then admitted to the interior of the bottles and their exterior is also cleaned by the perforated pipe-section at this point. When the bottles pass from under the hood 28, the water is cut off from 105 the nozzles and as the cleaned bottles reach the operator in their rotation they are removed and replaced by others.

I claim:

1. A bottle-rinsing machine comprising a 110 standard-supported basin, a rotatory hollow sectional reel mounted within the basin, the reel being provided with a hub having its bottom face provided with a series of horizontally disposed water-inlet apertures, a 115 non-rotatory water-supply ring having a horizontally disposed single aperture therein adapted to register with the reel apertures, a series of vertically disposed spray-nozzles in connection with each sector of the 120 hollow reel, posts extending from the reel, a unitary apertured bottle-supporting ring fitted over all of the spray-nozzles and independent thereof, collars extending from the bottle-supporting ring for connection with 125 the posts, and means in connection with the collars for securing said bottle-supporting ring in a fixed adjusted position upon the posts.

2. A bottle-rinsing machine comprising a 130

standard-supported basin, a rotating sectional hollow reel mounted within the basin, the reel being provided with a series of water-inlet apertures, a non-rotatory water-supply ring having a single aperture therein, adapted to register with the reel-apertures, vertically disposed spray-nozzles in connection with the hollow reel, an adjustable apertured bottle-supporting ring fitted over the spray-nozzles, and an adjustable bottle-shield disposed above said spray-nozzles.

3. A bottle-rinsing machine comprising a standard-supported basin, a rotatory sectional hollow reel mounted within the basin, the reel being provided with a series of water-inlet apertures, a non-rotatory water-supply ring having a single aperture therein, adapted to register with the reel apertures, means for holding the ring in yielding-connection with the reel, vertically disposed spray-nozzles in connection with the hollow reel, an adjustable apertured bottle-supporting ring carried by the reel, the apertures in the bottle-supporting ring being fitted over the spray-nozzles, a hood in connection with the basin, an adjustable bottle-shield carried by the hood and disposed above said spray-nozzles, a perforated pipe-section in connection with the shield, and a water-supply pipe in connection with the perforated pipe-section and non-rotatory water-supply ring.

4. A bottle-rinsing machine comprising a standard, a basin secured to the standard, a rotatory spindle, and a reel mounted upon the spindle, the reel comprising a hub secured to the spindle having hollow spokes, a series of hollow spokes connected with a series of hollow sectors independent of each other, vertical spray-nozzles extending from the hollow sectors, openings in the reel-hub in connection with each spoke, a non-rotatory water-supply ring having a single aperture therein adapted to register with the reel hub openings, means in connection with the standard holding the non-rotatory ring in yielding engagement with the reel-hub, and

a water-supply pipe in connection with said ring.

5. A bottle-rinsing machine comprising a hollow standard, a spindle revolvably mounted within the standard, an apertured, channeled ring secured to the standard, a hollow spoke-reel secured to the spindle having its hub-portion adapted to engage the upper face of the channeled ring, the hub-portion being provided with apertures adapted to register with the ring aperture, springs interposed between the standard and ring whereby the latter is held in yielding engagement with said hub-portion of the reel, non-communicating hollow sectors carried by the reel-spokes, each sector being in communication with one of said reel-spokes, spray-nozzles extending from the hollow sectors, a drip-pan connecting the standard and surrounding the reel sectors, a hood extending upwardly from the drip-pan and partially surrounding the same, and a spray-pipe extending within the hood, the spray-pipe being disposed above the plane of the spray-nozzles.

6. A bottle-rinsing machine comprising a rotatory hollow reel, having non-communicating sections, spray-nozzles carried by the sections, means for supplying water to the non-communicating sections successively, a hood disposed above the reel in such relation to the water-supply as to be over that section which is being supplied with water, an adjustable bottle shield carried by the hood and disposed above said spray-nozzles, a perforated pipe section in connection with the bottle shield, and a water-supply pipe in connection with the pipe section.

In testimony that I claim the foregoing I have hereunto set my hand at Milwaukee, in the county of Milwaukee and State of Wisconsin in the presence of two witnesses.

L. WEISCOPE.
